(57) **CLAIM**

The ornamental design for a crawl space door with frame as shown and described.

DESCRIPTION

FIG. 1 is a front perspective view of the crawl space door with frame;

FIG. 2 is a rear perspective view of the crawl space door with frame;

FIG. 3 is a front elevation view of the crawl space door with frame;

FIG. 4 is a rear elevation view of the crawl space door with frame;

FIG. 5 is a bottom plan view of the crawl space door with frame;

FIG. 6 is a top plan view of the crawl space door with frame;

FIG. 7 is a left side elevation view of the crawl space door with frame;

FIG. 8 is a right side elevation view of the crawl space door with frame;

FIG. 9 is a front perspective view of the door panel shown separately for clarity of illustration; and,

FIG. 10 is a rear perspective view of the door panel shown separately for clarity of illustration.

The broken lines in the drawings depicting the handles form no part of the claimed design.

1 Claim, 8 Drawing Sheets
